[57] **CLAIM**

The ornamental design for a fingernail clipper catcher, as shown and described.

DESCRIPTION

FIG. 1 is a front view of the fingernail clipper catcher of the present invention;

FIG. 2 is a back view of the fingernail clipper catcher of FIG. 1;

FIG. 3 is a left side view of the fingernail clipper catcher of FIG. 1;

FIG. 4 is a right side view of the fingernail clipper catcher of FIG. 1;

FIG. 5 is a top plan view of the fingernail clipper catcher of FIG. 1; and,

FIG. 6 is a bottom plan view of the fingernail clipper catcher of FIG. 1.

The undisclosed interior surfaces and inside edges on the rear surface of the clipper catcher form no part of the claimed design.
